UNITED STATES PATENT OFFICE.

ISAAC H. LESEM, OF ST. LOUIS, MISSOURI.

DESIGN FOR A HAND OR TOILET FAN.

55,062.

Specification for Design.

Patented May 4, 1920.

Application filed December 31, 1919. Serial No. 348,684. Term of patent 14 years.

To all whom it may concern:

Be it known that I, ISAAC H. LESEM, a citizen of the United States, residing at the city of St. Louis, State of Missouri, have invented a certain new, original, and ornamental Design for Hand or Toilet Fans, of which the following is a specification, reference being had to the accompanying drawing, forming a part thereof.

The drawing illustrates a hand or toilet fan embodying my new design, the Figures

1 and 2 being, respectively, elevational and sectional views of the fan.

My new design for hand or toilet fans comprises a blade A of fabricated sheet material having, by embossment, the configuration of a woven or braided body.

I claim:

The ornamental design for a hand or toilet fan substantially as shown and described.

ISAAC H. LESEM.
